UNITED STATES PATENT OFFICE.

JOHN WILLIAM NASMITH, OF STOCKPORT, ENGLAND.

COMBING-MACHINE.

1,239,123.

specification of Letters Patent. Patented Sept. 4, 1917.

Application filed August 7, 1911. Serial No. 642,725.

To all whom it may concern:

Be it known that I, JOHN WILLIAM NASMITH, of Stockport, England, have invented certain new and useful Improvements in 5 Combing-Machines, of which the following is a specification.

This invention relates to combing machines of the Heilmann type.

In machines of this type the nippers have 10 been given two kinds of movement: when receiving one kind of movement the nipper remains stationary in close proximity to the cylinder needles during the combing period, moves away toward the detaching 15 rollers, remains stationary again in the proper position in proximity to the detaching rollers during the detaching period, and then moves back toward the cylinder needles; when receiving the other kind of 20 movement they are made to reciprocate uninterruptedly between the combing point and the detaching rollers by means of a crank or an eccentric or a cam giving a motion approximating to that of a crank. 25 In the former case, when the movement is intermittent, the path followed by the point of the nipper between its two stationary positions has not hitherto been of great importance, but in the second case it is of 30 great importance and has hitherto been either a straight line or an arc of a circle, or has closely approximated to one of these.

As hereinafter described, the nipper must pass between two points and the path of the 35 nipper is such that during the combing it is not at a constant distance from the cylinder needles while traversing the last portion of the path at the rearward or combing end C; further the length of the path is 40 considerable and is determined by the diameters of the cylinder and the detaching roller.

The chief object of the present invention is to shorten the path so that the movement 45 of the heavy nipper may be reduced and it may follow a path that is much more favorable for its work: this path may be made much shorter than the paths followed by the nippers of combing machines hitherto constructed, and may be made to remain at 50 a constant distance from the needles at the rearward or combing end C.

According to this invention and with the above mentioned object in view I guide the 55 nipper point of a combing machine of the Heilmann type, by any suitable means,

along a desired path between the combing point and the detaching rollers. This may be effected by oscillating the nipper pivot to give the nipper a to and fro motion and 60 providing independent means for guiding the point of the nipper along any suitable path between the combing and detaching points.

In the accompanying drawings, 65

Figure 1 is a sectional side elevation showing one arrangement according to this invention;

Fig. 2 is sectional side elevation of a modification of the arrangement shown in 70 Fig. 1; and

Fig. 3 is a similar view showing another arrangement also according to this invention.

Fig. 4 is a diagrammatic side elevation 75 showing a preferred path of the nipper point.

In Fig. 4, A indicates a portion of the cylinder of a combing machine, 9 one of the detaching rollers, C the combing point, and 80 D the detaching point between which two points the nipper must pass.

First, referring more particularly to Fig. 1, one end of a nipper frame 1 is pivoted on a stud 2 fixed in a lever 3 adjustable 85 within certain limits on a shaft 4, which is caused to oscillate to and fro in the required manner by a crank eccentric or cam. In a suitable position near the other end of the nipper frame and fixed therein is a stud 90 5 which serves to carry a bowl 6 and on which may also pivot a top nipper arm 7. Suitably attached to but adjustable on the framing is the support or guide 8 upon which the bowl 6 runs as the nipper moves 95 to and fro, or the guide 8 may be made a fixture and the bowl 6 adjustable so as to set the nipper point at the proper distance from the cylinder needles. Any desired shape may be given to the guide 8 so that in combination with the movement of the pivot 2, the point of the nipper may be given any desired path, such as D C, Fig. 4, which during the rearward part is adjacent the periphery of the cylinder and rises at the 100 forward end to approach more or less directly the nip of the detaching rollers 9, 10. In this way the total reciprocating movement between the combing and detaching positions may be much reduced.

Fig. 2 shows an alternative method of guiding the nipper point. Attached to the

pin 5 is a link 11 pivoting on a pin 12 in the arm of a lever 13 keyed on a shaft 14 which is caused to oscillate at the proper time and in the proper manner so as in combination 5 with the to and fro motion of the frame 1, to guide the point of the nipper in any desired path.

Again, if it be desired to cause the nipper point during the whole of its path to follow 10 the periphery of the cylinder as when the usual Heilmann detaching method is used, this may be done (see Fig. 3) by giving the lever 3 the same radius as the cylinder and supporting the stud 5 in a link 15 also of 15 the same radius as 3 and pivoted at 16. Then if the point of the nipper be vertically above the center of the cylinder when centers 5 and 2 are vertically above centers 16 and 4 respectively the point of the nipper 20 will follow a path *d c* concentric with the cylinder.

The top nipper arm 7 (Fig. 1) has fixed in it a pin 17 upon which the slotted end of the rod 18 engages. The rod 18 carries 25 an adjustable finger 19 having a slot in its upper part through which the bar 20 freely passes. The rod 20 is pivoted in the back bar 21 fixed to the machine framing. On the rod 20 between the finger 19 and 30 the back 21 is a spiral spring 22 and on the rod 18 behind the back bar an adjustable stop collar 23. If the frame 1 moves to the right carrying with it the arm 7, it is obvious that after the nipper jaws are closed 35 the stop collar will be pushed away from the back bar and the spring 22 compressed, further pressing the jaws firmly together. On the other hand when the frame 1 moves to the left and the stop collar 23 has come 40 against the back bar the upper end of the arm carrying the pin 17 will be arrested while the pivot 5 is carried forward by the frame 1 and the nipper is thus opened. The pressure of the spring 22 pressing against 45 the finger 19 constantly keeps the rod 18 down on the pin 17, while permitting it to be easily lifted off and pushed to one side when the whole nipper can be lifted clear of the cylinder for the purpose described 50 in the specification of my application Serial No. 642,724, filed herewith.

It will be obvious that the details of construction may be varied without departing from this invention: for example means 55 other than those shown could be devised for

guiding the nipper along any desired path; or the end of the nipper frame that is remote from the point of the nipper may be supported and oscillated in any convenient manner other than those shown and described. I do not therefore confine myself to the constructions shown or to the precise paths indicated. 60

What I claim is:—

1. In a combing machine provided with 65 the usual combing, feeding and detaching means, a nipper adapted to hold the material during combing, means for actuating the nipper, and means for guiding the nipper during the combing, along a path which 70 changes independently of the movement of the nipper actuating means.

2. In a combing machine provided with the usual combing, feeding and detaching means, a nipper adapted to hold the material during combing, an oscillatory support for the nipper, means operated by oscillation of said support to actuate the nipper, and means for guiding the nipper during the combing, along a path which 75 changes independently of the movement of the nipper actuating means.

3. In a combing machine provided with the usual combing, feeding and detaching means, a rock shaft, an arm mounted on 85 said rock shaft, a nipper frame pivotally connected at one end to said arm, a nipper carried by the free end of said frame, and a cam supporting the free end of said frame, 90 said cam being shaped to guide the nipper during the combing along a path which changes independently of the movement of the nipper actuating means.

4. In a combing machine provided with the usual combing, feeding and detaching 95 means, a rock shaft, an arm mounted on said rock shaft, a nipper frame pivotally connected at one end to said arm, a nipper carried by the free end of said frame, and means situated between the rock shaft and 100 the nipper for guiding the latter, during the combing, along a path which changes independently of the movement of the nipper actuating means.

In testimony whereof I have affixed my 105 signature, in presence of two witnesses.

JOHN WILLIAM NASMITH.
